AUTOMATICALLY ADJUSTING BRAKE

Rudolph A. Goepfrich, South Bend, Ind., assignor
to Bendix Aviation Corporation, South Bend,
Ind., a corporation of Delaware

Original application August 1, 1942, Serial No.
453,237, now Patent No. 2,389,618, dated No-
vember 27, 1945. Divided and this application
August 27, 1945, Serial No. 612,731

7 Claims. (Cl. 188—79.5)

1

This invention relates to automatically adjusting brakes, and is particularly intended for brakes of the type in which one or more friction elements or shoes are forced outwardly into contact with a rotating drum. The present application is a division of application Serial No. 453,237, filed August 1, 1942, now Patent No. 2,389,618.

In general, the object of the present invention is to provide an improved construction of automatic adjustment mechanism of the type wherein a drum contact member is utilized to measure the amount of adjustment required. The improved adjustment mechanism disclosed in the present application both improves the efficiency of operation of the automatic adjuster and reduces the cost of manufacturing the same.

Other objects and advantages of the invention will become apparent during the following description. In the drawings:

Figure 1 is a section taken through a brake assembly which includes a drum actuated automatic adjustment; and

Figures 2, 3, and 4 are sections taken on the lines 2—2, 3—3, and 4—4, respectively, of Figure 1.

The brake shown in the drawing includes a rotatable drum 12, a nonrotatable support member or backing plate 14, two brake shoes 16 and 18 pivoted on backing plate 14 by means of anchor pins 20 and 22, and a hydraulic actuator 24 located between the free ends of the shoes and adapted to move the same outwardly into contact with the brake drum to provide a frictional resistance to rotation of the drum. Auxiliary mechanical shoe spreading mechanism comprising a thrust link 26 and a lever 28 having a pin-like element 27 integral therewith for engagement with said thrust link may also be incorporated in the brake assembly. Members 29 and 31 are provided to prevent lateral displacement of the shoe 16, and the shoe 18 and lever 28, respectively.

The shoes 16 and 18 are T-section shoes, each having a rim 30 and a web 32 normal to the rim. Secured to the outer surface of the rim of each shoe is a layer 34 of the usual friction lining material. As the brake is used, the lining material 34 gradually wears away, and it is the purpose of the present invention to provide improved means for automatically adjusting the released position of at least one of the shoes as the lining thereon is worn off. Provision of such automatic adjustment means results in the maintenance of a substantially constant clearance between the drum and the shoe when the latter is in released

position, and therefore the amount of pedal travel required to move the shoe into contact with the drum remains substantially the same, except of course when the drum expands appreciably due to excessive heat.

If the drum 12 be assumed to rotate in the counter-clockwise direction when the vehicle is moving forwardly, then the shoe 16 will be the self-energizing shoe a large portion of the time.

10 Therefore, because wearing away of the lining of shoe 16 occurs much faster than wearing away of the lining of shoe 18, the provision of an automatic adjuster for shoe 16 only will usually be adequate.

15 Lying against the web 32 of shoe 16 is a drum contact adjustment control member 36, the outer end of which extends through aligned shots 38 and 40 provided respectively in the rim 30 and lining 34 of the shoe. The outer surface 42 of member 36 is flush with the face 44 of lining 34, and therefore contacts the inner surface of drum 12 whenever the lining is moved against the drum. The member 36 may be made of any suitable material, but I have found it particularly convenient to form it of steel, because this is an inexpensive material, and may be readily shaped to the desired configuration.

Adjustment control member 36 is prevented from moving laterally by means of raised nibs 30 46 and 48 provided on web 32, said web normally being a sheet metal stamping which lends itself readily to the formation of the nibs 46 and 48.

Further guiding for the adjustment control member 36 is provided by an offset or raised portion 50 formed on said member 36 and extending into a slot 52 cut in the radially inner edge of web 32. Holding adjustment control member 36 tightly against the side of web 32 is a resilient element or leaf spring 54, which is secured by means of a rivet 56 to the offset portion 50 of member 36, and which has an edge 58 in contact with the side of web 32 opposite the surface which contacts member 36.

An inclined cam surface 60 is provided on one 45 side of adjustment control member 36, and this surface is in contact with the end of an arm 62 of bell crank lever 64. Lever 64 is fulcrumed on the web of shoe 16 by means of a pin 66. The other arm 68 of the lever has a folded over end portion 70 which is located on the opposite side of the shoe web from the main part of the lever, and which thereby assists in holding the lever firmly in position. The surface 72 of the lever contacts a stop member 74 which may be an eccentric supported on pin 76, which is carried by

backing plate 16. The purpose of the eccentric is to provide an initial manual adjustment for the brake shoe.

Operation of the automatic adjustment mechanism is as follows. As the lining of shoe 16 wears down with successive brake applications, the substantially non-wearing outer surface 42 of adjustment control member 36 is pushed in by contact with the brake drum, said member moving radially inward with respect to the rim and web of the shoe. As this movement of member 36 occurs, the cam surface 60 acts on arm 62 of lever 64 to move the lever in a clockwise direction about its fulcrum 66. This causes the surface 72 of the lever to be moved farther away from the shoe. Therefore, after a brake application which has caused member 36 to move inwardly, surface 72 of lever 64 will contact stop member 14 when the shoe is slightly farther from the stop member than it was prior to the brake application. This prevents return spring 18 from returning the shoe all the way to its former released position, and thus maintains a substantially constant clearance between the lining of shoe 16 and the inner surface of drum 12. Assuming the use of a conventional hydraulic system to operate the actuator 24, the left piston in said actuator will be caused to follow the upper end of shoe 16 outwardly, as the released position of the shoe is gradually changed by the automatic adjustment mechanism. In other words, there is a pressure urging the piston in actuator 24 to follow up shoe 16 as the shoe is adjusted, and additional fluid will be drawn in from the reservoir of the hydraulic master cylinder to compensate for the outward displacement of the released position of the piston. The end result is to retain substantially the amount of pedal travel reserve regardless of the amount of wear on the lining of brake shoe 16.

It will be apparent from the foregoing description that the several parts of the automatic adjustment mechanism are positively and efficiently maintained in operating position by means of relatively simple and inexpensive structural features. An additional advantage of the present arrangement is the avoidance of structural characteristics which would permit lining dust to clog the parts of the adjustment mechanism and prevent proper operation thereof.

Although a particular embodiment of my invention has been described, it will be understood by those skilled in the art that the object of the invention may be attained by the use of constructions different in certain respects from that disclosed without departing from the underlying principles of the invention. I therefore desire by the following claims to include within the scope of my invention all such variations and modifications by which substantially the results of my invention may be obtained through the use of substantially the same or equivalent means.

I claim:

1. In a brake having a drum, a backing plate, and a shoe adapted to be moved at times against the drum, automatic adjusting means for the shoe comprising a friction block extending through the shoe and having its face flush with the face of the shoe which contacts the drum, said friction block being shifted inwardly relative to the shoe by wear of the shoe, extrusions in the shoe web adjacent the sides of the friction block in combination with a projection on the friction block extending into an opening of the shoe web for guiding said friction block on the

shoe web, a lever pivoted to the shoe, a portion of the lever contacting one side of the friction block and adapted to rotate the lever on its pivot as the friction block moves inwardly, and a stop mounted on the backing plate and arranged to contact one end of the lever to hold the shoe in released position determined by the angular position of the lever.

2. In a brake having a drum, a backing plate, and a shoe adapted to be moved at times against the drum, automatic adjusting means for the shoe comprising a friction block extending through the shoe and having its face flush with the face of the shoe which contacts the drum, said friction block being shifted inwardly relative to the shoe by wear of the shoe, extrusions in the shoe web adjacent the sides of the friction block in combination with a projection on the friction block extending into an opening of the shoe web for guiding said friction block on the shoe web, means cooperating with the face of the shoe opposite that on which the friction block is mounted and adapted to frictionally engage the friction block on the shoe web, a lever pivoted to the shoe, a portion of the lever contacting one side of the friction block and adapted to rotate the lever on its pivot as the friction block moves inwardly, and a stop mounted on the backing plate and arranged to contact one end of the lever to hold the shoe in released position determined by the angular position of the lever.

3. In a brake having a rotatable drum and a non-rotatable support member, an automatically adjusting friction element cooperating with said drum comprising a T-section brake shoe carried by said support member and having a rim, a web at right angles thereto, and a layer of friction lining material on the rim adapted to contact the drum during braking, said rim and lining having a slot therethrough, an adjustment control member lying against one side of the shoe web and extending through said slot to bring its outer surface flush with the face of the lining, the shoe web having raised nibs contacting the sides of said adjustment control member to prevent lateral movement thereof, said shoe web also having a slot therein extending radially outwardly from the inner edge of the web, said adjustment control member having a raised portion guided in said web slot, a resilient element secured to said adjustment control member and bearing against the opposite side of the web to hold said member firmly against the web, said adjustment control member having an inclined cam surface formed on one side thereof, a lever carried by and fulcrumed on said shoe and contacting at one point the cam surface of the adjustment control member, said lever having a folded over end portion embracing the shoe web and thereby laterally restraining the lever, and a stop member mounted on the aforesaid support member and arranged to contact a point on said lever to determine the released position of the shoe in accordance with the angular position of the lever relative to the shoe, the relative angular position of the lever being gradually changed as lining wear causes the adjustment control member to move radially inwardly with respect to the shoe web.

4. In a brake having a rotatable drum and a non-rotatable support member, an automatically adjusting friction element cooperating with said drum comprising a T-section brake shoe carried by said support member and having a rim, a

tion lining material on the rim adapted to contact the drum during braking, said rim and lining having a slot therethrough, an adjustment control member lying against one side of the shoe web and extending through said slot to bring its outer surface flush with the face of the lining, the shoe web having raised nibs contacting the sides of said adjustment control member to prevent lateral movement thereof, said shoe web also having a slot therein extending radially outwardly from the inner edge of the web, said adjustment control member having a raised portion guided in said web slot, a resilient element secured to said adjustment control member and bearing against the opposite side of the web to hold said member firmly against the web, said adjustment control member having an inclined cam surface formed on one side thereof, a lever carried by and fulcrumed on said shoe and contacting at one point the cam surface of the adjustment control member, and a stop member mounted on the aforesaid support member and arranged to contact a point on said lever to determine the released position of the shoe in accordance with the angular position of the lever relative to the shoe, the relative angular position of the lever being gradually changed as lining wear causes the adjustment control member to move radially inwardly with respect to the shoe web.

5. In a brake having a rotatable drum and a non-rotatable support member, an automatically adjusting friction element cooperating with said drum comprising a T-section brake shoe carried by said support member and having a rim, a web at right angles thereto, and a layer of friction lining material on the rim adapted to contact the drum during braking, said rim and lining having a slot therethrough, an adjustment control member lying against one side of the shoe web and extending through said slot to bring its outer surface flush with the face of the lining, the shoe web having raised nibs contacting the sides of said adjustment control member to prevent lateral movement thereof, said shoe web also having a slot therein extending radially outwardly from the inner edge of the web, said adjustment control member having a raised portion guided in said web slot and also having an inclined cam surface formed on one side thereof, a lever carried by and fulcrumed on said shoe and contacting at one point the cam surface of the adjustment control member, and an abutment on the aforesaid support member arranged to contact a point on said lever to determine the released position of the shoe in accordance with the angular position of the lever relative to the shoe, the relative angular position of the lever being gradually changed as lining wear causes the adjustment control member to move radially inwardly with respect to the shoe web.

6. In a brake having a rotatable drum and a non-rotatable support member, an automatically adjusting friction element cooperating with said drum comprising a T-section brake shoe carried by said support member and having a rim, a web at right angles thereto, and a layer of friction lining material on the rim adapted to contact the drum during braking, said rim and lining having a slot therethrough, an adjustment control member lying against one side of the shoe web and extending through said slot to bring its outer surface flush with the face of the lining, the shoe web having raised nibs contacting the sides of said adjustment control member to prevent lateral movement thereof, said adjustment control member having an inclined cam surface formed on one side thereof, a lever carried by and fulcrumed on said shoe and contacting at one point the cam surface of the adjustment control member, and an abutment on the aforesaid support member arranged to contact a point on said lever to determine the released position of the shoe in accordance with the angular position of the lever relative to the shoe, the relative angular position of the lever being gradually changed as lining wear causes the adjustment control member to move radially inwardly with respect to the shoe web.

6. In a brake having a rotatable drum and a non-rotatable support member, an automatically adjusting friction element cooperating with said drum comprising a T-section brake shoe carried by said support member and having a rim, a web at right angles thereto, and a layer of friction lining material on the rim adapted to contact the drum during braking, said rim and lining having a slot therethrough, an adjustment control member lying against one side of the shoe web and extending through said slot to bring its outer surface flush with the face of the lining, the shoe web having raised nibs contacting the sides of said adjustment control member to prevent lateral movement thereof, said adjustment control member having an inclined cam surface formed on one side thereof, a lever carried by and fulcrumed on said shoe and contacting at one point the cam surface of the adjustment control member, and an abutment on the aforesaid support member arranged to contact a point on said lever to determine the released position of the shoe in accordance with the angular position of the lever relative to the shoe, the relative angular position of the lever being gradually changed as lining wear causes the adjustment control member to move radially inwardly with respect to the shoe web.

7. In a brake having a drum, a backing plate, and a shoe normally out of contact with the drum and constituted to be moved thereagainst, means for automatically maintaining the distance between the drum and shoe substantially fixed notwithstanding shoe wear comprising a friction block extending through the shoe and having a face portion terminating in flush relationship with the portion of the shoe which contacts the drum, said friction block being shifted inwardly relative to the shoe as the shoe wears, guide means for retaining the friction block in position, a lever pivoted to the shoe and having a portion in contact with one side of the friction block which is constructed and arranged to impart rotation to said lever as the friction block moves inwardly, and a stop mounted on the backing plate and arranged to contact one end of the lever to hold the shoe in released position determined by the angular position of the lever.

RUDOLPH A. GOEPFRICH.
